UNITED STATES PATENT OFFICE.

JAMES W. STONE, OF OWENSBOROUGH, KENTUCKY, ASSIGNOR OF ONE-HALF TO RUFUS P. DAY, OF SAME PLACE.

CHURN.

SPECIFICATION forming part of Letters Patent No. 248,364, dated October 18, 1881.

Application filed June 6, 1881. (Model.)

To all whom it may concern:

Be it known that I, JAMES W. STONE, a citizen of the United States, residing in the city of Owensborough, county of Daviess, and State 5 of Kentucky, have invented a new and useful Churn, to be constructed of galvanized iron or heavy tin, with wooden dasher-stem, of which the following is a specification.

My invention relates to churning; and it consists in the novel construction of parts which will first be described, and then pointed out in the claim.

Figure 1 of the drawings is a perspective view, partly in section. Fig. 2 represents a 15 perspective of the dasher. Fig. 3 is a perspective of the churn-cover; Fig. 4, a perspective of the cap or locking device for ventilator-cover.

In the accompanying drawings, A represents the vessel; A' A', the vessel-handle. B 20 is the inner vessel or cup. C C are two vertical rods, soldered to the rim of the cup B. D is a ring, soldered to the vertical rods C C and fitting closely to the inner side of the vessel A. The letter E represents the churn-cover. F F 25 are two raised semicircular slots on the top of said cover. G is the dasher-handle. H rep-

resents the reciprocating rotary dasher. K and h are the dasher-wings. L represents the cap or locking device. The letter M is the wire handle attached thereto, having projections m. The letter a is a strip, extending over a slot, b. c c are two rings, attached to ring D; e e, the cover-collar, encircling the dasher-handle G. g is the spindle on dasher-handle G.

It will be seen in Fig. 3 that by removing 35 the handle G, reciprocating rotary dasher H, and inner cup or vessel, B, and placing the locking device or cap L over the top of collar e e, the cover is thereby made liquid-tight, and the vessel A, when the cover is on, converted 40 into and may be conveniently used for an ordinary pail or ice-cream freezer.

I claim—

The cap L, having wire handle M and projections m, attached to said cap, in combination with churn-cover E, substantially as described, and for the purposes set forth. 45

JAMES W. STONE.
